Joseph Whitley Inventor:

UNITED STATES PATENT OFFICE.

JOSEPH WHITLEY, OF FLINT, MICHIGAN.

FIRE-ESCAPE.

SPECIFICATION forming part of Letters Patent No. 248,375, dated October 18, 1881.

Application filed July 2, 1881. (No model.)

To all whom it may concern:

Be it known that I, JOSEPH WHITLEY, of Flint, Genesee county, Michigan, have invented a new and valuable Improvement in Fire-Escapes; and I do hereby declare that the following is a full, clear, and exact description of the construction and operation of the same, reference being had to the annexed drawings, making a part of this specification, and to the letters and figures of reference marked thereon.

Figure 1 of drawings is a representation of a part sectional side elevation of my fire-escape. Fig. 2 is a sectional plan view, and Fig. 3 is a view of the ladder.

The nature of my invention consists in the construction and arrangement of a fire-escape, as will be hereinafter more fully set forth.

The annexed drawings, to which reference is made, fully illustrate my invention.

20 A represents an ordinary window-frame to which my fire-escape is attached.

B is a wooden-beam of any suitable dimensions, formed on its under side with a projection, B', as shown, and strengthened on both 25 sides with iron bars C C firmly bolted to the beam. The front end of the beam B is slotted to receive a pulley, D, which runs on a rod or axle, a, passing through and having its bearings in the beam and the strengthening-bars

30 C. Through the inner or rear end of the beam B is passed a hook, E, having threads on its upper end for the application of a nut, b. The beam B is to be laid across the window-sill A', in the manner shown in the drawings, and the

35 hook E placed under the inner end of the window-sill, and by tightening the nut b the beam is held firmly in its place.

To provide for or against any accident by the hook E slipping or otherwise coming loose,

a rod, G, is passed horizontally through the 40 inner end of the beam and its strengthening-bars, which rod is of such length as to extend entirely across the window and bear against both sides of the frame, thus forming additional holds or bearings for the beam. 45

H is a basket or similar receptacle, provided with loops d d, connected to a hook, e, on the end of the hoisting-rope I, which is passed over the pulley D, for lowering persons or goods from the burning building. This basket is also 50 provided with a rope, J, for guiding its descent and holding it out from the building.

The beam B is provided with a hook, K, for pulling it from floor to floor of the building, or it can be raised up from the outside by 55 means of an ordinary ladder, L.

What I claim as new, and desire to secure by Letters Patent, is—

1. The combination, with the beam B, provided with the projection B', strengthening-bars C C, and pulley D, of the recessed window-sill A', hook E, and nut b, substantially as described, and for the purpose set forth. 60

2. The combination, with the beam B, provided with the projection B', and recessed window-sill A', of the hook E, having nut b, and rod G, extending through a hole in the inner end of said beam and across both sides of the window-frame, substantially as described, and for the purpose set forth. 65

In testimony that I claim the above I have hereunto subscribed my name in the presence of two witnesses.

JOSEPH WHITLEY.
